METHOD OF AND APPARATUS FOR GENERATING AND SUPERHEATING STEAM

Application filed April 25, 1922. Serial No. 556,372.

The present invention relates to the generation and superheating of steam and is characterized by the absorption of radiant heat from the combustion chamber of a boiler furnace by which the steam is generated to obtain a substantial portion, usually 50% or more, of the total desired superheating effect, and by obtaining the remainder of the heat utilized in superheating the steam 10 wholly or mainly by contact with and conduction from the boiler furnace heating gases after the latter have been cooled somewhat by contact with heating surface of the boiler proper, so that the tendency for the 15 degrees of superheat secured by the absorption of radiant heat to diminish as the amount of steam generated increases and as the amount of excess air from the heating gases increases, is neutralized wholly or 20 in large part by the tendency of the degrees of superheat furnished by heat abstracted from the partially cooled heating gases to increase as the rate of steam generation increases and as the rate of excess air in the 25 heating gases increases.

In the practical carrying out of the invention, the radiant heat superheating effect is obtained by means of a so-called radiant heat superheater exposed to the interior of 30 the boiler combustion chamber and ordinarily incorporated in the wall thereof, and disposed out of the path of flow of any considerable portion of the heating gases so as to minimize the heat absorption of this 35 superheater by contact with and conduction from the heating gases as well as to minimize the oxidizing effect of the heating gases on the superheater. The remainder of the 40 desired superheating effect is obtained by means of a suitably proportioned ordinary superheater in the path of the heating gases leaving the combustion chamber and contacted by the latter after they have passed over more or less of the boiler heating surface 45 and have been correspondingly cooled.

The manner in which the two superheaters arranged as described cooperate to secure a more uniform degree of superheat than can be obtained with either, and particularly 50 with the radiant heat superheater, when used

alone, will be apparent from the following explanation. In the operation of an ordinary boiler furnace the rate of fuel combustion must be varied either manually or automatically in general accordance with the 55 boiler load, i. e. the rate at which steam is generated and withdrawn from the boiler, and the weight of the heating gases therefore varies in approximate proportion to the boiler load, though ordinarily the proportion is not exact because the furnace chamber temperature increases somewhat as the load increases and in practice the combustion efficiency is usually somewhat higher at 60 heavy boiler loads than at light loads. In either type of superheater the degrees of superheat imparted to the steam passing through the superheater depends of course on the amount of heat absorbed by the superheater and on the amount of steam to be 65 thereby superheated. In the radiant heat superheater the rate of heat absorption depends almost entirely on the furnace chamber temperature, and the effect of an increase or decrease in boiler load is to 70 respectively reduce or increase the degrees of superheat because the change in the amount of steam to be superheated is substantially greater than the effect on the amount of heat absorbed of the relatively small changes in 75 furnace chamber temperature occurring as a result of changes in the rate of combustion. Since the effect of an increase in the amount of excess air in the heating gases is to lower 80 the furnace chamber temperature as well as the temperature of the heating gases, the superheating effect of the radiant heat superheater diminishes and increases as the amount of excess air increases and diminishes. 85

In the case of the superheater heated by contact with and conduction from the heating gases, the rate of heat absorption depends both on the weight of the heating gases sweeping over the superheater and on the 90 temperature of those gases. With an increase in the boiler load throughout what may be regarded as a normal load variation, say from 50% to 200% of rating, the 95 degrees of superheat given the steam by this 100

superheater increases, for while the effect of the increased weight of heating gases is substantially neutralized by the increased weight of steam to be superheated, the gases come to the superheater at increasingly higher temperatures as the load increases.

In practice at a certain high boiler load which is different for different conditions, the superheat furnished by the ordinary gas contact heated superheater reaches a maximum and then diminishes as the load is further increased. This results primarily from the fact that the higher loads can be carried only with an amount of excess air in the heating gases less than ordinarily exists at lighter loads, though the fact that at the higher boiler loads the rate of increase in temperature of the heating gases reaching the superheater diminishes, may also contribute to the decrease in superheat at very high boiler loads. The effect of an increase or decrease in the amount of excess air on the gas contact heat superheater is to respectively increase or decrease the degrees of superheat obtained, because the change in the weight of heating gases flowing past the superheater is a more important factor in this connection than is the corresponding change in heating gas temperature. Thus throughout the normal range of boiler load variation the effect of a change in the boiler load on the superheating effect of one superheater is neutralized or compensated for in whole or in part by the corresponding change in the superheating effect of the other superheater and this is true also of the effect on the superheaters of a change in the percentage of excess air supplied to the furnace.

The relative portions of the total superheating effect furnished by the two superheaters which will give the best results from a practical standpoint vary with conditions, and depends in part on such considerations as the relative cost of construction and maintenance of the two types of superheaters and the space conditions in the boiler furnace installation. The radiant heat superheater requires less heating surface and ordinarily is less expensive to construct and maintain than an ordinary superheater giving the same superheating effect and hence it is ordinarily desirable from a practical standpoint to obtain as much of the superheating effect with the radiant superheater as is possible, consistent with the required degree of uniformity in superheat under varying conditions of load and combustion efficiency, though in some installations, the construction cost of the superheater provisions required for a given superheating effect may well be less when this effect is obtained with two small superheaters, one of each type than when obtained by a single large superheater of either type. This is due to the

fact that the effectiveness and hence the construction cost per unit of capacity with each type of superheater depends upon its location in the boiler setting. The most favorable location for the radiant heat superheater is in the zones of the furnace walls receiving the maximum radiation. These zones are comparatively narrow and when the radiant heat superheater capacity required is relatively large, these zones may not be large enough to receive all of the superheater surface, and the portions of said surface than located outside of those zones are much less effective than in some cases not more than one quarter as effective as, portions of similar area in the high temperature zones. The most effective location for an ordinary or gas contact heated superheater is that in which the superheater is swept by heating gases which have traversed only a small portion of the boiler heating surface and have been cooled only as little as is necessary to permit them to come into contact with the superheater without undue deterioration of the latter. This most favorable location is ordinarily too small to receive more than a comparatively small sized superheater. An ordinary superheater located near the combustion chamber will give a superheating effect which varies less on changes in boiler load than is the case with the radiant heat superheater, though when the ordinary superheater is located relatively near to the boiler stack outlet, the variation in its superheating effect as a result of changes in boiler loads is more marked than in the case of the radiant heat superheater. In practice however, it is not usually possible to obtain a high superheating effect, say 200° F. or above, with an ordinary superheater installed in a water tube boiler of large capacity such as is now generally used in large power stations, because there is not available space for the location of an adequate amount of superheating surface close to the furnace chamber, and when located at a point nearer the stack where more space is or may be made available, the increased amount of superheater surface required entails a prohibitive cost of construction.

Proposals have heretofore been made to employ two superheaters in a single boiler in such fashion that one superheater would, and the other would not receive some radiant heat, but in such proposals there has been no thought of obtaining the uniformity in superheat which is secured with the arrangement herein described, and the superheater receiving radiant heat has been disposed and intended to be heated largely by contact with and conduction from the heating gases, thereby making the variation in its superheater effect on changes in the boiler load or combustion conditions an uncertain quan-

6 tity. Moreover, a superheater exposed to a vigorous flow of burning gases at the combustion chamber temperature is subject to a much more severe deteriorating effect than is a superheater out of the path of flow of such gases though exposed to the same temperature, and a superheater heated wholly or mainly by radiant heat may be constructed in a manner better adapting it to resist the deteriorating conditions to which it is subjected than is possible with a superheater intended to receive much of its heat by contact with and conduction from heating gases.

10 In the accompanying drawings and descriptive matter I have illustrated and described one embodiment of my invention in a boiler of one of the many types with which the invention may be carried out. The embodiment illustrated also comprises certain

20 novel details of combination.

Of the drawings:

Fig. 1 is a general sectional view of a boiler showing the two superheaters combined therewith.

25 Fig. 2 is a section on the line 2—2 of Fig. 1.

Fig. 3 is an enlarged side elevation of the radiant heat superheater.

30 The boiler here shown is of the Stirling or Connelly type, and contains an ordinary or standard superheater 1, located back of the first bank of boiler tubes and provided with the Foster type of superheater rings. There is also installed in the front wall of 35 the fire chamber 2 a radiant heat superheater 3, which is connected in the series with the superheater 1 by the connection 4. Steam from the boiler passes first through superheater 1 and then through superheater 3, 40 the outlet header of the latter being indicated at 5.

The radiant heat superheater is composed of tubes 6 encased in cast iron envelopes 7, which are separated by refractory blocks 8. 45 L-shaped bars or plates 9, (preferably of steel) are embedded in the front walls and serve as supports or stiffeners for the iron encased superheater tubes which at intervals are bolted to said plates as shown at 10.

50 Preferably the connecting conduit 4 between the two superheaters is disposed as shown and extends up to a point above the water level in the upper drums. This enables the radiant heat superheater to be 55 flooded in starting up the boiler without flooding the upper superheater 1 and without requiring the use of a valve between the two superheaters. Such flooding is usually effected to prevent destructive heating of 60 the radiant heat superheater until the boiler is connected to the steam line.

As indicated above, space limitations, commercial considerations, and load or combustion conditions, mitigate against the use 65 of either a standard or a radiant heat super-

heater in such boilers as the one illustrated, of sufficient capacity to be used alone, but the two relatively small superheaters arranged as set forth will, in the aggregate, meet all practical requirements, besides 70 yielding a uniform superheat.

Having now described my invention, what I claim is:

1. The method of generating and superheating steam characterized by the direct 75 absorption by metallic bodies of radiant heat from the combustion chamber of the boiler in which the steam is generated to furnish a portion of the desired superheating effect and by the absorption of such 80 additional heat as is required for the desired total superheating effect wholly or largely from the heating gases leaving said combustion chamber after the latter have been partially cooled by contact with the 85 water heating surfaces of the boiler to thereby maintain a substantially uniform total superheating effect.

2. The method of generating and superheating steam characterized by the direct 90 absorption by metallic bodies of radiant heat from the combustion chamber to the boiler furnace in which the steam is generated to furnish a substantial portion of the desired superheating effect, and by the 95 absorption of the additional heat required for the superheating effect, wholly or largely from the heating gases leaving said combustion chamber after the latter have been partially cooled by contact with the water 100 heating surface of the boiler, to thereby neutralize or compensate to a substantial degree for the decreases in the superheating effect due to radiant heat which occur when the rate of steam generation or the 105 amount of excess air supplied to the furnace increases, by the increase in superheating effect due to the heat abstracted from the partially cooled heating gases occurring on an increase in boiler load or in 110 the amount of excess air.

3. Apparatus for generating and superheating steam comprising a water tube boiler and its furnace, a superheater having exposed metal walls located in position to absorb heat substantially solely by radiation from the combustion chamber of the boiler furnace, a second superheater located in position to absorb heat by contact with the boiler heating gases after the latter have 115 been partially cooled by contact with the heating surface of the boiler proper, and connections for passing the steam generated in the boiler through both superheaters whereby the relative decrease in superheating effect of the first mentioned superheater resulting from an increase in the rate of steam generation or in the amount of excess air supplied to the furnace is neutralized or compensated for by the simultaneous increase 120 125 130

in relative heating effect of the second superheater.

4. Apparatus for generating and superheating steam comprising a water tube boiler and its furnace, a superheater having exposed metal walls located out of the main path of heating gas flow, but in position to absorb heat mainly by radiation from the combustion chamber of the boiler furnace, 10 a second superheater located in position to absorb heat by contact with the boiler heating gases after the latter have been partially cooled by contact with the heating surface of the boiler proper, and connections for 15 passing the steam generated in the boiler through both superheaters whereby the relative decrease in superheating effect of the first mentioned superheater resulting from an increase in the rate of steam generation 20 or in the amount of excess air supplied to the furnace is neutralized or compensated for by the simultaneous increase in relative heating effect of the second superheater.

5. Apparatus for generating and superheating steam comprising a water tube boiler of the Stirling type and its furnace, 25 a superheater having exposed metal walls located in the front wall of the combustion chamber of the furnace and adapted to 30 absorb heat wholly or mainly by radiation from the combustion chamber of the boiler furnace and a second superheater located between the first and second banks of boiler tubes.

- 35 6. Apparatus for generating and superheating steam comprising a water tube boiler and its furnace, a superheater located in the path of the heating gases after the latter have traversed a portion of the boiler 40 heating surface, a second superheater located out of the main path of heating gas flow, but in position to absorb heat mainly by radiation from the combustion chamber of the furnace, and means for 45 passing the steam withdrawn from the boiler first through one and then through the other superheater, said means comprising a conduit connecting the superheaters and including a portion extending upward 50 from the second superheater to a level above the boiler water level whereby the filling of said second superheater with water will not flood the first mentioned superheater.

- 55 In testimony whereof I hereto affix my signature

WALES S. BUELL.
